CLAIM

We claim the ornamental design for a portion of an electrical component, such as a radio, audio component, battery charger or radio/charger, as shown and described.

DESCRIPTION

FIG. 1 is a right side view of a portion of an electrical component; and,

FIG. 2 is a front view of the portion of the electrical component shown in FIG. 1.

The present application is directed to the shape and contour of the design illustrated in the drawings. The broken line showing of the environment is for illustrative purposes only and forms no part of the claimed design. The broken lines which define the boundaries of the claimed design form no part thereof.
